(57) **CLAIM**

The ornamental design for an in-line ground fault circuit interrupter, as shown and described.

DESCRIPTION

FIG. 1 is a front perspective view of an in-line ground fault circuit interrupter showing my new design;

FIG. 2 is a front view of the in-line ground fault circuit interrupter shown in FIG. 1;

FIG. 3 is a left side view of the in-line ground fault circuit interrupter shown in FIG. 1;

FIG. 4 is a rear view of the in-line ground fault circuit interrupter shown in FIG. 1; and,

FIG. 5 is a bottom view of the in-line ground fault circuit interrupter shown in FIG. 1.
